(57) **CLAIM**

The ornamental design for a detachable power supply for data logger, as shown and described.

DESCRIPTION

FIG. 1 is a top front right perspective view of another embodiment of a detachable power supply for a data logger showing our new design.

FIG. 2 is a bottom front left perspective view thereof.

FIG. 3 is a bottom rear perspective view thereof.

FIG. 4 is a rear elevation view thereof.

FIG. 5 is a front elevation view thereof.

FIG. 6 is a top plan view thereof.

FIG. 7 is a bottom plan view thereof.

FIG. 8 is a right side elevation view thereof; and,

FIG. 9 is a left side elevation view thereof.

The broken lines in the drawings illustrate portions of the detachable power supply for a data logger that form no part of the claimed design.

1 Claim, 6 Drawing Sheets
